UNITED STATES PATENT OFFICE.

JOHN PATERSON, JR., OF EDINBURG, NORTH DAKOTA.

HOISTING-HOOK.

1,386,583.

Specification of Letters Patent.

Patented Aug. 2, 1921.

Application filed April 3, 1918. Serial No. 226,517.

To all whom it may concern:

Be it known that I, JOHN PATERSON, Jr., a citizen of the United States, and a resident of Edinburg, in the county of Walsh and State of North Dakota, have invented certain new and useful Improvements in Hoisting - Hooks, of which the following is a specification.

My present invention relates to a self-releasing hook, and particularly to a device of this character intended to be used at the end of a cable or chain of a hoist, as for instance on life boats, with a railroad wrecker, and in other like connections.

The principal object of my invention is to provide a hook of this character which will be caught within a ring and which will hold as long as the weight draws thereon, the structure of the hook being such that when the pull is released by slackening of the cable or chain, the hook will automatically move to a position in which it is released.

Another object is to so construct the hook that when the movable parts thereof swing to the released position the bill of the hook is swung or moved in a line corresponding substantially to the curve thereof and the hook is thus positively moved from a position in which it might reengage or again catch within the ring from which it is to release.

Yet another object is to provide a structure in which the hook is carried by a friction roller, thus insuring easy movement of the same, and which hook structure will not become fouled with guy cables or the like, after it has been released from the part or structure which has been hoisted or moved.

Further objects of my invention will appear in the following detailed description, taken in connection with the accompanying drawing, forming a part of this specification, and in which drawing:

Figure 1 is a view in elevation of a hook constructed after the manner of my invention and showing the same swung to a hoisting position.

Fig. 2 is an elevational view illustrating the hook in its other extreme position, and with parts broken away and illustrated in sections to more clearly disclose the structure and arrangement of the parts.

Fig. 3 is a sectional view taken transversely through the hook member and in part through the member by which the hook is carried.

In the drawing, where similar characters refer to similar parts throughout the views, A designates the hook member which is carried by the supporting member B, this supporting member having a ring C passed through an eye thereof for securement of the hoisting chain or cable D.

The hook member A is made up substantially in the form of an elongated link at one side, one end of which forms the bill 4 of the hook portion proper. The bill 4 is preferably tapered so that it may be more readily caught through a ring or the like, and will not offer obstruction when being withdrawn therefrom, and at its remaining end the member A has an enlargement or weight portion 5. This enlargement at 5 is preferably extended as shown in the drawing, so that a great portion of the weight thereof is thrown outside of the link form of the member to one side of its major axis. A curved slot 6 is formed transversely through the member A in the middle portion thereof, opposite to the hook proper and the supporting member B is bifurcated at 7 to receive this slotted portion of the hook member A, a horizontal pivot 8 being secured across the bifurcated end of the member B and received through the slot 6. To relieve friction of the member A when the same swings about the pivot 8, a friction roller 9 is revolvably mounted thereon, it of course being understood that this friction roller is given a loose fit within the slot 6.

The supporting member B has an eye 10 at the upper end thereof through which the ring C is received, and as the hoisting chain or cable D is secured within this ring C, the supporting member is suspended with the bifurcated end thereof depending downwardly. The member A is so formed that when the bill 4 of the hook portion proper thereof is caught through a ring 11, under the bail of a bucket, or through or around some other like portion, the lower portion of the link form will be directly vertically below the pivot 8, and the parts will carry substantially as shown in Fig. 1. When the part carried by the hook is brought to the desired position and comes to rest, the chain or cable D will be slackened, and in consequence the pulling strain between the pivot 8 and the looped end of the hook member A adjacent the bill 4 will be released. The enlarged end 5 of the member A is made sufficiently heavy so that it overbalances the

bill end and the hook portion proper, and when the pulling strain is relieved, this end 5 will cause the member A to be initially swung around the pivot 8 and then slide there- 5 upon so that the member will be carried to the position shown in Fig. 2, where the friction roller 9 will come to bearing against the remaining end of the slotted opening 6. 10 As the member A swings around the friction roller and travels through the slight movement permitted by the formation of the slotted opening, the bill 4 of the hook portion proper will be moved in a swinging path and will also be quickly moved bodily 15 in a direction that the bill 4 is withdrawn endwise from the ring 11. The opening at the bifurcated end 7 of the supporting member B might be formed to present a stop to limit movement of the member A in either 20 or both directions, or the formation of this opening might be such that movement of the member A is unrestrained and the extreme positions thereof are determined by the balance of the load and the overbalanc- 25 ing of the hook portion by the weighted enlarged end, these positions being shown in Figs. 1 and 2.

While I have herein described the structure as being made up and mounted in a 30 particular manner, it will be appreciated that changes in the conditions of use would doubtless require variations in the form, and perhaps in the arrangement, of the parts. Much stress is laid upon the mounting of 35 the hook member A in conjunction with the supporting member B so that the member A may have swinging and also shifting movement as an entirety, as it is due to this combined movement that the bill is posi- 40 tively withdrawn endwise from the engaged and hoisting positions.

Changes in details may be made without departing from the spirit or scope of my invention; but,

45 I claim:

1. A self-releasing hoisting hook comprising in combination, a hook member

formed in the shape of an elongated link open at one side, provided with a weight disposed at the same side of the major axis 50 of the body as its open portion, and having an arcuate slot formed transversely through its end portion opposite to the hook proper, and a supporting member for said hook member, including a pivot extending 55 through the said slot of the hook member to pendently support the same by engagement at the one end of the slot nearest said weight when a load of considerable magnitude is 60 pendently supported from the hook portion proper, and to engage the other end of the arcuate slot when the load is relieved sufficient to permit swinging of the hook member responsive to the force of gravity acting upon said weighted portion of the hook 65 member, the hook member initially swinging and then riding on said pivot in the descent of the weighted portion so as to quickly release the load.

2. A self releasing hoisting hook comprising in combination, a hook member formed in the shape of an elongated link open at one side, provided with an enlargement at the same side of the major axis as the open portion, and disposed upon the upper end 70 to provide a structure having a majority of the weight of the entire structure to one side, of the major axis, said hook having an arcuate slot formed transversely through its end portion opposite the weighted end, and a supporting member for said hook including a pivot extending through said slot 75 to pendently support the same by engagement at an end of the slot nearest the weight, for supporting a load upon the hooked end of the hook member, said hook adapted to swing laterally when a slack occurs in a supported load, under force of gravity by the dropping of its weighted end, and riding 80 of the pivot in the arcuate slot to release the load, said supporting member adapted to limit the releasing movement of the hook member.

JOHN PATERSON, JR.
